DESIGN FOR A CONTAINER FOR POKER CHIPS

Thomas K. Almroth, Toledo, Ohio

Application June 6, 1945, Serial No. 119,940

Term of patent 3½ years

(Cl. D34—5)

To all whom it may concern:

Be it known that I, Thomas K. Almroth, a citizen of the United States and a resident of Toledo, Lucas County, Ohio, have invented a new, original, and ornamental Design for a Container for Poker Chips, of which the following is a specification, reference being had to the accompanying drawing, forming a part thereof.

In the drawing:

Figure 3 is a perspective view similar to Figure 2 with the lower portions of the container moved outwardly to position of use.

I claim:

The ornamental design for a container for poker chips, as shown.

THOMAS K. ALMROTH.
